AUTOMATICALLY DETONATED PROJECTILE

Leslie J. Anderson, Indianapolis, Ind., assignor
to Radio Corporation of America, a corporation
of Delaware

Application April 30, 1942, Serial No. 441,081

6 Claims. (Cl. 102—70.2)

This invention relates generally to projectiles and particularly to automatically detonated projectiles actuated by sound waves of predetermined characteristics.

Heretofore various types of automatically detonated projectiles have been known and various methods of actuating the detonator mechanism have been devised. While both electromagnetic and electrostatic means provide satisfactory operation of detonating devices, the apparatus required is quite complicated and inherently delicate, leading to considerable difficulty in the design of satisfactory equipment. Acoustically operated detonators are much more rugged and do not require the careful adjustment or delicate equipment common to the radio types.

It is an object of this invention to provide improved means for acoustically detonating a projectile in response to sound waves of predetermined frequency characteristics. Another object of the invention is to provide improved means for supporting the projectile in space for a considerable period of time to facilitate the formation of an effective aerial barrage. Still another object is to provide improved means for equipping a projectile with a suitable parachute mechanism, operable by a timing mechanism within the projectile, acoustically detonating the projectile by sound waves of predetermined frequency characteristics, and deenergizing the detonator mechanism after a predetermined time interval.

The invention will be described by reference to the drawing, of which Figure 1 is an elevational view of one embodiment of the invention, and Figure 2 is a schematic diagram of the detonator and timing mechanisms. Similar reference numerals are applied to similar elements throughout the drawing.

Referring to Fig. 1, a projectile having an outer casing 1 is provided with a suitable explosive charge 2. A detonator 3 of the type utilizing a flash filament is disposed in proximity to the explosive charge 2. The projectile casing includes a hinged nose portion 5 connected to the base portion 1 by an invisible hinge 6. The nose portion is held in a closed position by the catch 8 including a notch 10. A locking sear 10 contacts the latch 9 at the notch 10 to hold the nose portion in a closed position against the tension of the spring 8. It should be understood that any other suitable trigger operated latch mechanism may be utilized and that this invention is not to be limited to the precise mechanical details disclosed herein. A timing mechanism 4, which may be of any well known type, and which should

preferably be adjustable, both as to rate and initial operation, is suitably connected to the sear 10 to release the latch 9 at a predetermined interval after the shell is fired. This interval should 5 preferably be approximately the time required for the shell to reach the highest point in its trajectory. A suitably folded parachute 7 is enclosed within the hinged projectile nose 5, in such a manner that it will be released to support the 10 projectile when the timing mechanism actuates the sear 10 and the spring 8 causes the projectile nose to open.

The detonating mechanism includes a comparatively large diaphragm 11 connected in operable 15 relation to a carbon, or other well known type, microphone 12, proportioned and adapted to provide maximum output at some predetermined frequency, such as, for example, the sound produced by an airplane in flight.

20 Referring to Fig. 2, the timing mechanism 4 actuates a commutator, having a contact portion 17 and an insulated portion 18, to complete the circuit between one terminal of the microphone 12 and one terminal of the primary of the transformer 14. The remaining terminal of the microphone 12 is connected to one terminal of a battery 13. The remaining terminal of the battery 13 is connected to the remaining terminal of the primary of the transformer 14. The detonator 25 filament 3 is connected across the secondary of the transformer 14. It will be apparent that the timing mechanism will not only release the parachute, as described heretofore, but will energize and deenergize the detonator mechanism, depending upon the relative position of the commutator contact section with the sliding contacts in connection therewith. By suitably adjusting the rate and phase of the timing mechanism and commutator, the detonator mechanism may be arranged 30 to be responsive to sounds of predetermined frequency for the time interval beginning with the release of the parachute and ending at some predetermined altitude. With such an arrangement the projectile, if unexploded upon reaching the particular selected altitude, becomes 35 insensitive to later received sounds and may be recovered for future use.

In operation, the resonant characteristics of 40 the diaphragm 11, the microphone 12, and the transformer 14, may be determined by proportioning the physical dimensions and electrical design thereof in any manner well known in the electrical or acoustics arts. Substantially no current will flow in the secondary of the transformer 45 55 14 when the current in the transformer primary

continuous. However, when sound waves, of a frequency to which the diaphragm resonates, are applied to provide large amplitude vibration thereto, the microphone resistance is varied at the resonant frequency, thereby providing a pulsing current which is transferred through the transformer 14 to energize the detonator 3. If desired, the diaphragm may be utilized in combination with an acoustic resonator, not shown, to increase its selectivity of frequency response.

I claim as my invention:

1. A projectile including an explosive charge, a detonator for said charge, a timing mechanism, and a parachute all enclosed within said projectile, means responsive to predetermined operation of said timing mechanism for releasing said parachute to support said projectile in space, means disposed within said projectile for deriving energy in response to the impingement thereon of sound waves, means for applying said energy to said detonator for actuating said detonator, and means responsive to predetermined operation of said timing mechanism and operable subsequent to said release of said parachute for selectively conditioning said sound responsive means and said energy applying means for actuating said detonator.
2. A device of the type described in claim 1 including means disposed in said projectile for conditioning said sound responsive means and said energy applying means after a predetermined time interval of said selective conditioning.
3. A projectile including an explosive charge, a detonator for said charge, a timing mechanism, and a parachute all enclosed within said projectile, means responsive to predetermined operation of said timing mechanism for releasing said parachute to support said projectile in space, resonant means disposed within said projectile for deriving energy in response to the impingement thereon of sound waves, means for applying said energy to said detonator for actuating said detonator, and means responsive to predetermined operation of said timing mechanism and operable subsequent to said release of said parachute for selectively conditioning said sound responsive means and said energy applying means for actuating said detonator.
4. A projectile including an explosive charge, a detonator for said charge, a timing mechanism,

5. and a parachute all enclosed within said projectile, means responsive to predetermined operation of said timing mechanism for releasing said parachute to support said projectile in space, means including a microphone disposed within said projectile for deriving energy in response to the impingement thereon of sound waves, means for applying said energy to said detonator for actuating said detonator, and means responsive to predetermined operation of said timing mechanism and operable subsequent to said release of said parachute for selectively conditioning said sound responsive means and said energy applying means for actuating said detonator.
10. 5. A projectile including an explosive charge, a detonator for said charge, a timing mechanism, and a parachute all enclosed within said projectile, means responsive to predetermined operation of said timing mechanism for releasing said parachute to support said projectile in space, means including a microphone having a diaphragm tuned to a predetermined frequency disposed within said projectile for deriving energy in response to the impingement thereon of sound waves, means for applying said energy to said detonator for actuating said detonator, and means responsive to predetermined operation of said timing mechanism and operable subsequent to said release of said parachute for selectively conditioning said sound responsive means and said energy applying means for actuating said detonator.
15. 6. A projectile including an explosive charge, a detonator for said charge, a timing mechanism, and a parachute enclosed within said projectile, means responsive to predetermined operation of said timing mechanism for releasing said parachute to support said projectile in space, means including a circuit having predetermined frequency characteristics disposed within said projectile for deriving energy in response to the impingement thereon of sound waves, means for applying said energy to said detonator for actuating said detonator, and means responsive to predetermined operation of said timing mechanism and operable subsequent to said release of said parachute for selectively conditioning said sound responsive means and energy applying means for actuating said detonator.
20. 30. 40. 45. LESLIE J. ANDERSON.
